CLAIM

The ornamental design for a roller guide for a fishing rod, as shown and described.

DESCRIPTION

FIG. 1 is a perspective view of a roller guide for a fishing rod, showing my new design;

FIG. 2 is a front elevational view, the rear being a mirror image thereof;

FIG. 3 is a top plan view thereof;

FIG. 4 is a left side elevational view thereof;

FIG. 5 is a right side elevational view thereof;

FIG. 6 is a bottom plan view thereof; and,

FIG. 7 is a rear perspective view of a second embodiment, the front perspective being a mirror image thereof.

FIG. 1

FIG. 2

FIG. 4

FIG. 3

FIG. 6

FIG. 5

FIG. 7
